GAS PRESSURE OPERATED THRUSTER
Stanley J. Kent, Philadelphia, Pa., assignor to the United States of America as represented by the Secretary of the Army

Filed Aug. 29, 1963, Ser. No. 305,562

1 Claim. (Cl. 60—26.1)

(Granted under Title 35, U.S. Code (1952), sec. 266)

The invention described herein may be manufactured and used by or for the Government for governmental purposes without the payment to me of any royalty thereon.

This invention relates to thrusters of the type wherein a piston, coupled to a load device, is moved in a cylinder by gas pressure resulting from the firing of an explosive cartridge. It provides an improved thruster including means whereby the cartridge is firmly seated at the time it is fired and the cartridge case is thereafter utilized to unlock the piston from the cylinder.

This improved thruster is similar in several respects to that of a copending application of Albert M. Stott, Serial No. 173,593, filed February 15, 1962, for Thruster, now Patent No. 3,133,408, issued May 19, 1964. It differs from the thruster of the aforesaid application in that (1) the gas pressure utilized to actuate the firing pin is also utilized to firmly seat the cartridge at the time it is fired, and (2) the gas generated by the firing of the cartridge is utilized both to move the cartridge case in a manner to unlock the piston from the cylinder and to move the piston.

Where the cartridge is held in position by a threaded connection, vibration, such as that incident to the operation of aircraft, can cause loosening of the thread. A loosely seated cartridge absorbs energy and reduces the effective energy of the firing pin. This can result in ignition failure. The present invention avoids this difficulty by means including a hollow cylindrical member or barrel which (1) functions as a firing pin guideway, (2) is pressed against the cartridge by the same gas pressure that actuates the firing pin, and (3) is actuated by the gas generated by the firing of the cartridge to move the cartridge case in a manner to unlock the piston from the cylinder out of which it is thereafter driven.

The invention will be better understood from the following description when considered in connection with the accompanying drawings and its scope is indicated by the appended claim.

Referring to the drawings:

FIG. 1 is an end view of the thruster, and

FIG. 2 is a sectional view taken along the line 2—2 of FIG. 1.

The thruster illustrated by these figures includes a cylinder 10 onto one end of which is threaded a trunnion-cap 11 having a gas inlet 12. A hollow piston 13 is movable in and extensible from the cylinder 10. This piston is closed at its outer end 14, is spaced from the cylinder to form an annular recess 15, has orifices 16 opening from the interior of the piston into the recess 15, and has a cartridge 17 positioned in its inner end. For some purposes it may also enclose a propellant charge 18 which is ignited by the firing of the cartridge.

The cartridge 17 has a large diameter section 19 and a

2

small diameter section 20. In the illustrated position of the cartridge, the large diameter section functions to maintain keys 21 in an internal groove of the cylinder 10 thereby interlocking the cylinder and the piston. When the case of the cartridge is moved rearward as herein-after explained, the small diameter section 20 is brought into registry with the keys 21 and the piston is released from the cylinder.

Interlinked with the cartridge 17 is a barrel 22 which is biased against the cartridge by a spring 23 and is releasably coupled to a firing pin 24 by a shear pin 25. For preventing gas leakage, the firing pin 24 has an O-ring 26, while barrel 22 has O-ring 27 and backup ring 28 and cylinder 10 has O-ring 29 and backup ring 30. In the operation of the above described thruster, a gas pressure applied through the inlet 12 forces the barrel 22 against the cartridge 17, shears the pin 25 and drives the firing pin 24 against the percussion primer of the cartridge. The firing of the cartridge generates a gas pressure within the piston and fires the charge 18 if utilized. The resulting gas pressure is applied through the orifices 16 and the recess 15 to the forward end of the barrel 22. As a result the barrel moves rearward carrying with the case of the cartridge 17. At a certain point in this rearward movement, the small diameter section 20 comes into registry with the keys 21 and the piston is released from the cylinder. The propellant 18 may be incorporated in the cartridge 17 when the volume of the cartridge is compatible with the thrust and propellant requirements.

I claim:

The combination of
a cylinder having an internal groove,
a hollow piston movable in said cylinder and extensible
therefrom, the forward end of said piston being closed
and said piston being spaced from said cylinder to
form therebetween an annular recess closed at its
forward end by an internal flange of said cylinder,
means forming a passageway between the interior of
said piston and said recess,
a cartridge positioned in the rearward end of said
piston and having small and large diameter sections,
locking means extending from said large diameter sec-
tion through said piston into said internal groove,
a floating barrel interlinked with said cartridge and
movable in said cylinder,
a spring urging said barrel and said cartridge against
the rearward end of said piston, and
means for firing said cartridge whereby there is pro-
duced a gas pressure extending from said piston
through said passageway and said recess to said barrel
and said barrel is forced against the tension of said
spring to move said small diameter section into aline-
ment with said locking means and release said piston
from said cylinder.
